(57) **CLAIM**

The ornamental design for a game station, as shown and described.

DESCRIPTION

FIG. 1 is a front perspective view of a game station in accordance with one embodiment of the present invention; FIG. 2 is a first end view of the game station of FIG. 1, it being understood that an opposing end view is the same; FIG. 3 is a front plan view of the game station of FIG. 1; FIG. 4 is a top view of the game station of FIG. 1; FIG. 5 is a bottom view of the game station of FIG. 1; FIG. 6 is a rear plan view of the game station of FIG. 1; FIG. 7 is a front perspective of a game station in accordance with another embodiment of the present invention; FIG. 8 is a first end view of the game station of FIG. 7, it being understood that an opposing end view is the same; FIG. 9 is a front plan view of the game station of FIG. 7; FIG. 10 is a top view of the game station of FIG. 7; FIG. 11 is a bottom view of the game station of FIG. 7; and, FIG. 12 is a rear plan view of the game station of FIG. 7. This design patent application claims priority to U.S. Utility patent application Ser. No. 09/750,742, filed on Dec. 28, 2000, entitled “Game Station.”
